(57) CLAIM

The ornamental design for the food holder, as shown and described.

DESCRIPTION

FIG. 1 is a perspective view of the food holder of the present invention;

FIG. 2 is a first side elevational view thereof;

FIG. 3 is a second side elevational view thereof;

FIG. 4 is a third side elevational view thereof;

FIG. 5 is a fourth side elevational view thereof;

FIG. 6 is a top plan view thereof; and,

FIG. 7 is a bottom plan view thereof.

The broken lines in the drawings illustrate the portions of the design that form no part of the claim.
